D34/28

FIG. 1 is a perspective view of a fluidic power actuator
showing my new design;

FIG. 2 is a front elevational view hereof;

FIG. 3 is a rear elevational view hereof;

FIG. 4 is a top plan view hereof;

FIG. 5 is a bottom plan view hereof;

FIG. 6 is a left side elevational view hereof; and

FIG. 7 is a right side elevational view hereof.

FIG. 1

FIG. 2

FIG. 3

FIG. 4

FIG. 5

FIG. 6

FIG. 7
